APPARATUS FOR CRUSH DRESSING
GRINDING WHEELS

John. C. Wilson, Springfield, Ohio, assignor to
The Thompson Grinder Company, Springfield,
Ohio, a corporation of Ohio.

Application February 8, 1946, Serial No. 646,314

6 Claims. (Cl. 125—11).

1

This invention relates to method and apparatus for grinding workpieces and is especially concerned with a method and apparatus for grinding employing a crushing roll for shaping the grinding wheel.

In the present grinding of workpieces, it has been found that a grinding wheel may be shaped to a very exact configuration by employing a crushing roll as a dressing member. A crushing roll consists of a metallic roll, preferably hardened steel, which is forced against the wheel while both the roll and the wheel are operating at reduced surface speed. The effect of such an operation is to crush the bonding which holds the particles of grinding material in the wheel and, thus to transfer to the wheel the configuration of the crushing roll.

In a dressing operation of this type, it is important that the peripheral speeds of the wheel and roll be identical in order to produce the best results. While this is automatically accomplished when the roll is of a simple configuration, it is not true when the roll has relatively deep grooves therein. In such a roll, the wheel and roll will slip relatively at some point along their line of contact and wearing of the roll will result which will reduce the accuracy of the workpiece produced on the machine.

The primary object of the present invention is to provide an improved method and apparatus for crush forming a grinding wheel wherein the configuration includes portions at substantially different radial distances from the wheel axis.

Still another object is to provide an improved crushing roll for dressing a grinding wheel in which different parts of the roll may rotate at different speeds in order to maintain the peripheral speed of the roll equal to the peripheral speed of the wheel during a dressing cycle.

It is still another object of the present invention to provide a crush dressing roll which is divided into segments by means of which the shape of the roll may be modified.

These and other objects and advantages become more apparent upon reference to the following specification taken together with the accompanying drawings in which:

Figure 1 is an elevational view of a grinding machine adapted for practicing the methods of this invention;

Figure 2 is a side view of the machine of Figure 1 showing the grinding wheel drive motor and the slow speed motor which drives the grinding wheel during the dressing cycle;

Figure 3 is a view showing one type of over-

2

running clutch adapted for connecting the slow speed motor with the spindle shaft.

Figure 4 is a sectional view taken substantially along the line 4—4 of Figure 1;

5. Figure 5 is a view taken substantially along the line 5—5 of Figure 1 and shows the grinding wheel being dressed; and

Figures 6 and 7 are views showing different types of crushing rolls constructed according to this invention.

Referring to the drawings, 10 indicates the bed of a grinder on which is reciprocably mounted a table 12 to be driven by a motor 14 carried in the said bed.

15. Connected with the bed or fixedly mounted adjacent thereto is a column 16 that supports a saddle 18 for vertical reciprocation by means of the nut and screw arrangement at 20, the said saddle, in turn, supporting the wheelhead structure at 22 which is adapted for reciprocation transversely in the said saddle.

25. Rotatable within the wheelhead 22, as by means of the shaft 24, is a grinding wheel 26. The shaft 24 is connected to be driven at grinding speeds by a motor 28 during which time the workpiece 30 may be reciprocated relative to the wheel and have ground thereon the configuration of the wheel.

30. In order to form the wheel to the desired shape, there is mounted on the table 12 a roller generally indicated at 32 which is pivotally mounted in bracket 34. To dress the wheel 26, the motor 28 is deenergized to bring the wheel to a halt and the table 12 is thereafter actuated to bring the roller 32 directly under the said wheel. The wheel and roll are then brought together under pressure by feeding the wheel downwardly by the nut and screw arrangement at 20. The wheel is then driven at a reduced speed while being urged

40. toward the roller 32, the said driving being accomplished by a motor 36 which drives through reduction gearing 38 and an overrunning clutch 40 into the shaft 24. After the wheel and roll have been fed toward each other a predetermined amount, the rotation of the wheel is halted and the dressing operation is complete. Preferably, the feeding together of the wheel and roll takes

45. place intermittently and the halting of the wheel after dressing takes place while the said wheel and roll are still together and under pressure.

50. The overrunning clutch at 40 is indicated at Figure 3 and will be seen to comprise a sleeve member 42 and a member 44 rotatable therein and the rollers 46 which are adapted to driv-
55. ingly interconnect the members 42 and 44 in one

direction of relative rotation and to permit free movement therebetween in the other direction of relative rotation.

Referring to Figure 4, there is shown in section the workpiece 30 and the wheel 26. It will be noted that the workpiece comprises a pair of recesses 48 and 50 which necessitates the upstanding ribs 52 and 54 on the wheel 26. The wheel 26 is shown in Figure 5 as being dressed by the crushing roller 32 and it will be noted that the ribs 52 and 54 on the wheel lie in corresponding recesses in the roll 32. The actual peripheral speed of the surfaces of the ribs 52 and 54 is considerably greater than the speed of the surfaces indicated at 56 and 58. Accordingly, if the roll 32 were formed of one piece, as is usually done, there would be slipping between the wheel and the roll at either the surface of the ribs or the surfaces 56 and 58 or both, the result being considerable wear on the roll itself.

In order to overcome this difficulty, this invention proposes to construct the roll 32 from a plurality of segments indicated at 60, 62, 64, and 66 and to individually journal the said segments on the supporting shaft 68 as by the bearings 70. The shaft 68 includes the flange 72 at one side thereof and a threaded portion which receives a nut 74 at the other side thereof. The nut 74 is adapted for being located in position by the set screw 76 so that the aforementioned plurality of segments may be closely held together while being free to rotate relatively. The shaft 68 is, in turn, journalled in the bracket 32' by the bearings 78 at either end thereof.

By dividing the roll 32 into a plurality of segments, or discs, and permitting the segments to rotate freely relatively, the peripheral speed of the roller is maintained very near to that of the grinding wheel and a minimum of slippage therebetween takes place. This substantially increases the life of the roller and maintains greater accuracy in the workpieces produced in the grinding machine.

Figure 6 illustrates an arrangement wherein there is a wheel 80 having the active portions 82 and 84 to be dressed. For dressing these portions, there is provided a roll consisting of the segments, or discs, 86 and 88 which are separated by a spacer 90 and which are individually journalled by the bearings 92 and 94 on the shaft 96. The spacing collar 98 is of such a size that the segments 86 and 88 are spaced apart exactly the required distance properly to form the active surfaces on the wheel 80. Should it be desired or necessary to adjust the spacing of the said segments, the collar 98 may be replaced by one of a different size, or the collar 98 may include shims, the number of which may be varied for adjusting the distance between the segments. Thus, in Figure 6 the segments are separately journalled for independent rotation in order to maintain their peripheral speed equal to that of the wheel while the collar 98 provides means for adjusting the exact transverse spacing of the said segments and, therefore, of the active surfaces on the wheel which is being dressed.

In Figure 7, there is a similar arrangement wherein a wheel 100 has the edge portions 102 and 104 and a central portion 106 all of which are to be dressed to a predetermined configuration. The dressing roll in Figure 7 consists of the end portions 108 and 110 and the central portions 112 all of which are individually journalled on the shaft 114 and closely but loosely retained thereon between the collar 116 and nut 118. The

arrangement in Figure 7 is such that the exact configuration of the wheel 100 may be varied across its entire width by replacing the segments 112, or by removing the said segments from the shaft 114 and machining off a predetermined amount from the inside surface of one or both thereof.

This invention then provides for a method of crushing a wheel having relatively deep grooves therearound while insuring a relatively long life of the crushing roller. The method of this invention also insures greater accuracy of workpieces when the same are ground by a grinding wheel having grooves or upstanding ridges thereon by insuring that the crushing roller employed for dressing the wheel will maintain its accuracy over a long period of time. This invention further provides a method for dressing a wheel by a crushing roll wherein the configuration of the wheel may be modified without replacing the entire roll.

It will be understood that this invention is susceptible to modification in order to adopt it to different usages and conditions and, accordingly, it is desired to comprehend such modifications within this invention as may fall within the scope of the appended claims.

I claim:

1. As a new article of manufacture, a multi-part crushing roll for crush forming a grinding wheel to a predetermined contour comprising: a plurality of individual annular segments arranged side by side and each adapted for dressing a different annular part of the wheel to be formed, said segments taken as a unit having a contour complementary to that to be formed on the wheel; and means supporting the said segments in rigid axial alignment and for free rotation relative to each other.

2. As a new article of manufacture, a multi-part crushing roll for crush forming a grinding wheel to a predetermined contour comprising: a plurality of individual annular segments arranged side by side and each adapted for dressing a different annular part of the wheel to be formed, said segments taken as a unit having a contour complementary to that to be formed on the wheel; means supporting the said segments in rigid axial alignment and for free rotation relative to each other, and means for bringing said wheel and roll together for the simultaneous application of all of said segments to said wheel.

3. In a crush dressing device, a bracket; a shaft journalled in said bracket and a multi-part roll carried on said shaft in fixed axial position relative to said shaft, said roll comprising a plurality of annular segments adjacently arranged, bearing means supporting each of said segments on said shaft for individually free rotation relative thereto, said segments taken as a group being of substantially the same axial length as the part of the wheel to be dressed thereby forming a compound roller by which the wheel to be dressed can be formed by the application of said segments to the grinding wheel by a single movement of said wheel and roll relatively.

4. In a device for dressing a grinding wheel; a stationary bracket; a shaft carried by said bracket having a shoulder; a roll of substantially the same axial length as the part of the wheel to be dressed mounted on said shaft against said shoulder and a nut adjustable on said shaft for retaining said roll against said shoulder, said roll being subdivided into a plurality of parts

along planes at right angles to the axis of said shaft; means supporting each of said parts on said shaft for free rotation relative thereto, each of said parts being adapted for dressing an individual annular part of said wheel.

5. In an apparatus for dressing a grinding wheel; a plurality of axially aligned cylindrical members and each adapted for dressing a different axial part of the periphery of a grinding wheel when pressed thereagainst; a shaft supporting said members for free individual rotation; and means retaining said members on said shaft in a predetermined spaced relationship comprising collar means between said members, a shoulder at one end of said shaft and adjustable abutment means at the other end of said shaft; the said spaced relationship of said members corresponding to the spacing on the wheel to be dressed of the parts of the wheel the members are to dress, whereby the wheel can be completely dressed by said members in a single operation.

6. The combination in a grinding machine for grinding workpieces having alternate ribs and recesses; of a grinding wheel having alternate ribs and recesses extending annularly therearound and a dressing roll for shaping said wheel by pressure, said roll comprising a plurality of

individual segments shaped to correspond to individual annular parts of said wheel and some thereof being adapted for forming the said recesses in said wheel and other thereof being adapted for forming the said ribs on said wheel; a shaft supporting said segments for individual free rotation about a common axis; and means retaining said segments on said shaft in rigid axial alignment with each other so that the configuration which they form as a unit is complementary to the form of the wheel to be dressed, whereby the wheel can be fully dressed by said roll in a single operation.
